HALTER

William H. Crandall, Oakland, Calif.

Application October 17, 1932. Serial No. 638,088

4 Claims. (Cl. 54—24)

This invention relates to a halter, such as employed for horses when tying them up in a stall or the like, and particularly to a halter which is constructed of rope or like material.

5 The object of the present invention is to generally improve and simplify the construction and operation of halters of the character described; to provide a halter which will be inexpensive to manufacture and which will be made 10 of rope or like material to obtain maximum strength and durability; to provide a halter which is adjustable to heads of varying size and which may be quickly applied and removed; and further, to provide a halter which is provided 15 with metal reinforcements where the halter rope is attached so as to reduce wear to a minimum.

The halter is shown by way of illustration in the accompanying drawing, in which—

Fig. 1 is a perspective view showing the halter 20 applied to the horse's head.

Fig. 2 is a perspective view of the halter by itself.

Fig. 3 is an enlarged detail view showing the metal reinforced portion of the chin piece of the 25 halter.

Fig. 4 is a cross section taken on line IV—IV of Fig. 3.

Fig. 5 is a longitudinal section taken on line V—V of Fig. 4.

30 Referring to the drawing in detail, and particularly Figs. 1 and 2, it will be noted that the halter is formed from two pieces of rope, a short piece forming a nose piece 3 and a portion of the chin piece, as indicated at 4, and a long piece 25 which forms the crown, the cheeks, and throat latch of the halter. The long rope commences at the point indicated at 5 where it is secured by a pair of clamping bands 6. The rope then extends downwardly, as indicated at 7, and is 40 passed through a pair of clamping bands 8 and 8a. The rope is next passed through an eye member 9a where it doubles back and passes through the clamps 8 and 8a. It then extends upwardly, as indicated at 9, and passes through 45 the eye member 10 which serves to receive a snap latch generally indicated at 11. It here doubles back on itself and is extended forward to form one cheek piece 12. It is extended to the nose piece where it passes through a pair of 50 clamping bands 13 and passes under the chin, as at 14, and up on the other side and through a pair of clamping bands 15 then rearwardly to form the second cheek piece 16. It again passes through the clamping band 6 then upwardly over 55 the head, as indicated at 17, and down the op-

posite side where it passes through the snap latch 11. It doubles back on itself and again passes over the head, as indicated at 18, and finally passes through an adjustable holding latch 19, this latch being secured to the halter 60 between the ropes which are secured by the clamps 6.

The portions of the rope 17 and 18 which pass over the head form the crown piece of the halter. These portions are held together by a pair of 65 ring clamps 20. The rope, however, passes loosely through them and as the free end of the rope passes through the adjustable holding latch 19, the length of the crown piece may be adjusted to suit heads of varying size and length. The 70 clamps 13 and 15 rigidly secure the short rope 3 forming the nose piece and a part of the chin piece to the forward ends of the cheek pieces 12 and 16. The free ends of the short rope 3 meet centrally under the chin, as indicated at 21, 75 see Fig. 5, but the free ends are here rigidly secured by three sets of clamping bands, such as indicated at 22, 23, and 24. These clamping bands serve three functions; first, that of securing the free ends 4 of the short rope forming the 80 nose piece and part of the chin portion of the halter; secondly, they function to secure the halter, as indicated at 25; and third, they function as a support for a ring 26 to which the 85 halter rope, not here shown, is attached.

The holder or retainer 25 is formed of a heavy round wire and is bent to form an elongated loop, the free ends of the loop being laid between the ropes 4 and 14, see Fig. 4, and being clamped and secured by the bands 22, 23 and 24. 90 This elongated loop retains the ring 26 in a central position on the chin piece and while it gives the ring free movement it still limits its movement laterally on the chin piece and it retains the ring in engagement with one or another of the clamping rings 22, 23 and 24. Thus, when a pull is exerted on the halter rope the wear and tear is taken up by the clamping bands 22, 23 and 24, and the rope forming the halter is saved from excessive wear. The ring 26 does not only 95 function to retain the halter rope but it also carries the eye member 9 forming the forward portion of the throat latch, that is, the rope section between the clamps 8 and 8a may be termed a throat latch and the rearwardly extending portions 7 and 9 may be called the throat pieces, as they hang under the throat of the horse at a point below the crown piece, as clearly shown in Fig. 1. The length of the throat latch may be 100 adjusted by moving the clamp 8a forwardly or 105 110

rearwardly, and then securing it by clamping it rigidly in position, the forward clamp 8 being always permanently clamped in place.

In actual use the halter is applied by unsnapping the latch 11, the nose piece is slipped over the nose of the horse, and the crown is thrown over the head behind the ears, the latch is then snapped into place. Conversely, when removing the halter, it is only necessary to release the latch 11 and slip the halter off, hence the halter can be quickly applied or released.

A halter constructed as shown has great strength and is exceedingly durable. The only place subjected to wear of any extent is that portion of the chin piece where the ring 26 is supported, as the pull of the halter rope will be applied thereto, but as the chin piece is reinforced by the clamping bands 22, 23 and 24, all wear is taken up by these bands and the halter as such is for all practical purposes indestructible. The throat latch may be readily adjusted when fitting the halter for the first time on the horse by sliding the clamp 8a rearwardly or forwardly, as the case may be, and by adjusting the crown piece comprising the rope sections 17 and 18. Once adjusted, the clamp 8 is squeezed tight with pliers or like tool and the halter is thus adjusted and may be indefinitely used. But inasmuch as the clamp 8a may be opened by spreading it, the halter may be readjusted for another horse if so desired.

While certain features of the present invention are more or less specifically described, I wish it understood that various changes may be resorted to within the scope of the appended claims. Similarly, that the materials and finish of the several parts employed may be such as the manufacturer may decide, or varying conditions or uses may demand.

Having thus described my invention, what I claim and desire to secure by Letters Patent is—

1. A halter of the character described compris-

ing a piece of rope adapted to encircle an animal's nose and having ends meeting beneath the chin, a second piece of rope forming cheek pieces and a throat latch and having a portion disposed alongside the meeting ends of the first piece, means clamping the ends of the first rope to the second rope, a ring retainer secured to the ropes by said clamping means, and a ring surrounding said clamping means and passing through said retainer.

2. A halter of the character described comprising a piece of rope adapted to encircle an animal's nose and having ends meeting beneath the chin, a second piece of rope forming cheek pieces and a throat latch and having a portion disposed alongside the meeting ends of the first piece, means clamping the ends of the first rope to the second rope, a ring retainer secured to the ropes by said clamping means, and a ring encircling both ropes and restricted by said retainer to movement along the ropes throughout the portion covered by the clamping means.

3. In a halter having a nose piece with ends meeting beneath the chin and a second piece lying alongside said meeting ends, metal clamps encircling said second piece and said ends, a ring encircling said metal clamps, and retaining means preventing contact of said ring with said nose piece and said second piece of the halter.

4. A halter of the character described comprising a piece of rope for encircling an animal's nose and having ends meeting beneath the chin, a second piece of rope, clamping means joining said pieces of rope and connecting parts of the second piece to form cheek pieces, a crown piece and a throat latch, a detachable connection between one side of the crown piece and the throat latch, means clamping the second piece to said first named piece at the piece ends thereof, a ring carried by said means, and a metal member connecting said throat latch and said ring.
